UNITED STATES PATENT OFFICE.

JEAN PIERRE GELAS, OF ST. ETIENNE, FRANCE.

DESIGN FOR A PATTERN FOR TEXTILE FABRICS.

SPECIFICATION forming part of Design No. 22,179, dated January 31, 1893.

Application filed November 28, 1892. Serial No. 453,423. Term of patent 3½ years.

To all whom it may concern:

Be it known that I, JEAN PIERRE GELAS, of St. Etienne, Department of Loire, France, have invented and produced a new and original 5 Design for a Pattern for Textile Fabrics, of which the following is a specification, reference being had to the accompanying drawing, forming a part thereof.

The pattern shown is intended for button o stock.

The figure is a plan view of a strip of button stock showing my design.

The leading feature of my design is the button-like figure which is produced upon the 5 stock, and which consists of intersecting band-like figures, each figure being composed of parallel strands. The strip of stock 10, has the button-like figures 11 produced at intervals thereon, each button-like figure being

made up of right angled intersecting band-like figures 12 and 13, each composed of parallel strands, while between the band-like figures 12, and apparently wound around the band-like figures 13, are short bands 14, the shorter band-like figures 14 being also produced at or near the outer portions of the band-like figures 13 and outside of the band-like figures 12. The groundwork of the button-like figure has a hatched appearance, the lines running mainly at angles to the band-like figures 12 and 13.

I claim—

The design for a pattern for textile fabrics herein shown and described.

JEAN PIERRE GELAS.
